US0D1058721S

(12) **United States Design Patent** (10) **Patent No.:** **US D1,058,721 S**
(45) **Date of Patent:** **** Jan. 21, 2025**

(54) **FITNESS EQUIPMENT**

(71) Applicant: **Yantai Qijiao Trading Co., Ltd.**,
Yantai (CN)

(72) Inventor: **Lianying Sun**, Yantai (CN)

(73) Assignee: **Yantai Qijiao Trading Co., Ltd.**,
Yantai (CN)

(**) Term: **15 Years**

(21) Appl. No.: **29/956,695**

(22) Filed: **Aug. 8, 2024**

(30) **Foreign Application Priority Data**

Jun. 28, 2024 (CN) 202430402101.6

(51) LOC (15) Cl. **21-02**

(52) U.S. Cl.

USPC **D21/673**; D21/676

(58) **Field of Classification Search**

USPC D21/662, 673, 675, 676, 677, 679, 680,
D21/681, 682, 684, 686

CPC A63B 23/03541; A63B 21/0628; A63B
21/4047; A63B 23/1209

(57) **CLAIM**

The ornamental design for a fitness equipment, as shown and described.

DESCRIPTION

FIG. 1 is a front perspective view of a fitness equipment, showing my new design;

FIG. 2 is a rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof;

FIG. 9 is an enlarged detail view of area 9 in FIG. 1 thereof;

FIG. 10 is an enlarged detail view of area 10 in FIG. 1 thereof;

FIG. 11 is an enlarged detail view of area 11 in FIG. 1 thereof; and,

FIG. 12 is an enlarged detail view of area 12 in FIG. 1.

The broken lines in the drawings illustrate the portions of the fitness equipment, which form no part of the claimed design. The dash-dot-dash broken lines encircling the enlarged views are for annotative purposes only and form no part of the claim thereof.

1 Claim, 12 Drawing Sheets
